Primary Examiner — Jennifer Rivard(74) *Attorney, Agent, or Firm* — Joanne N. Pappas; Kevin C. Johnson; Steven W. Miller(57) **CLAIM**

The ornamental design for a razor guard, as shown and described.

DESCRIPTION

FIG. 1 is a top perspective view of a design for a razor guard of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is bottom perspective view thereof.

The broken lines illustrate the environment and form no part of the claimed design. The dash dot dash broken lines illustrate the bounds of the claim and form no part of the claimed design.
